UNITED STATES PATENT OFFICE

MORITZ BEHR, OF HOUSTON, TEXAS

CIGARETTE AND MATCH CONTAINER

Application filed March 11, 1930. Serial No. 434,973.

This invention relates to a cigarette and match container particularly adapted to be worn by bathers, and has for its primary object to provide, in a manner as hereinafter set forth, a container of such class which may be expeditiously secured in position by the belt of a bathing suit, and which is constructed in a manner to eliminate all sharp edges or corners to prevent the possibility 10 of injury to the wearer or to anyone coming in contact with the wearer.

A further object of the invention is to provide a container of the character aforesaid which is provided with an opening of 15 appropriate size and shape to permit the insertion of cigarettes into the container without bending or breaking the cigarettes, and to further permit the housing of a package of matches within the closure for the opening.

20 A further object of the invention is to provide a container primarily designed for use by bathers in carrying cigarettes and matches as aforesaid, but which may be utilized by bathers for containing other articles, such 25 as coins, jewelry, powder puffs, cosmetics, and the like.

With the foregoing and other objects in view, the invention consists of the novel construction, combination and arrangement of 30 parts as hereinafter more particularly described, and as illustrated in the accompanying drawings wherein is shown an embodiment of the invention, but it is to be understood that the description and drawings are 35 to be taken as illustrative and that the invention is intended to be limited only by the scope of the claim hereunto appended.

In the accompanying drawings in which 40 like numerals are employed to designate like parts throughout the several views:

Figure 1 is a perspective view of a container in accordance with this invention showing the same in association with a belt.

45 Figure 2 is a horizontal section through the embodiment shown in Figure 1.

Figure 3 is a vertical section therethrough.

Referring to the drawings in detail, the 50 numeral 1 designates the body portion of my container which is integrally formed of a water-proof material, preferably hard rub-

ber, and which forms a compartment adapted to contain cigarettes. The body 1 is of materially greater length than width and is formed with rounded edges and corners as indicated at 2 and 3 respectively, in order 55 that the body may have no sharp projections which might stick into the person of the wearer or into the person of anyone coming in contact with the wearer. Extending along the sides of the body 1, in spaced relation 60 thereto, are a pair of strips 4 which are circular in cross section, and the end portions of which are secured to or formed integrally with the side faces of the body. The strips 4 are arranged in proximity to the back of the 65 container in order that a belt, such as 5, may be extended between each strip and the container and extend across the container at the rear face of the body 1.

At the front thereof, the body 1 is formed 70 with an opening 6 which is encircled by a forwardly projecting, annular flange 7 which is substantially flush with the upper and side edges of the body 1, and which is spaced a material distance from the lower edge of the 75 body 1. The flange 7 is exteriorly threaded and terminates at its free edge in an inturned resilient bead 8. As illustrated in Figure 3 the flange 7 projects a substantial distance 80 from the body portion and is of appropriate 85 diameter to form a compartment in communication with the body portion compartment adapted to contain a package of matches, such as 9, such compartment providing a retaining means for the cigarettes in the body 90 portion compartment. The opening 6 is provided with a closure cap 10 which is formed with an internally threaded flange 11 engaging the external threads of the flange 7. When the cap 10 is secured in position, the 95 inner face thereof bears against the inturned bead 8 formed on the flange 7 whereby a seal is provided at the outer edge of the flange 7. The bead 8 further forms a retainer to prevent the matches or other articles from 100 inadvertently escaping from the container when the cover 10 is removed therefrom.

Projecting from the outer face of the cover 10 is a keeper 12 to which is connected one end of a flexible element 13, the opposite end 100

of which is secured to one of the strips 4. The element 13 may be formed of any suitable, relatively soft material, such as that comprising a fish line, which is capable of resisting deterioration by its contact with salt water and the like.

It is thought that the many advantages of a container in accordance with this invention will be readily apparent, and although, the 10 preferred embodiment of the invention is as illustrated and described, it is to be understood that changes in the size, shape and arrangement of parts may be resorted to, so long as such changes fall within the scope of 15 the invention as defined in the appended claim.

What I claim is:

A container comprising, a body portion forming a compartment adapted to contain 20 cigarettes and having its forward wall formed with an opening, an externally threaded flange projecting forwardly a substantial distance from the body portion in circumferential relation to the opening and 25 forming a compartment in communication with the body portion compartment adapted to contain matches and providing a retaining means for the cigarettes, and a cover for said compartments including an internally 30 threaded flange threaded onto the externally threaded flange, said externally threaded flange terminating at its free edge in an in-turned bead providing a retaining means for the matches and bearing against the inner 35 face of the cover when the latter is in closure position to provide a seal.

In testimony whereof, I affix my signature hereto.

MORITZ BEHR.
